UNITED STATES PATENT OFFICE.

EDWARD B. ENTWISLE, OF JOHNSTOWN, PENNSYLVANIA, ASSIGNOR TO
THE LORAIN STEEL COMPANY, A CORPORATION OF PENNSYLVANIA.

RAILWAY-TRACK STRUCTURE.

SPECIFICATION forming part of Letters Patent No. 691,616, dated January 21, 1902.

Application filed June 26, 1901. Serial No. 66,082. (No model.)

To all whom it may concern:

Be it known that I, EDWARD B. ENTWISLE, of Johnstown, in the county of Cambria and State of Pennsylvania, have invented a new and useful Improvement in Railway-Track Structures, of which the following is a full, clear, and exact description, reference being had to the accompanying drawings, which form a part of this specification.

10 My invention has relation to certain new and useful improvements in railway-track structures, and more particularly to crossing structures such as are used where the rails of a steam-road intersect those of a street or 15 electric road.

The object of my invention is to provide a crossing structure of rigid and durable character in which all those portions which are subject to the greatest wear are formed of a 20 solid piece or body of a more durable nature than the other parts of the structure and which, if required, can be removed and replaced by a new piece.

With this object in view my invention consists in a crossing structure composed of rails properly fitted and joined to form a central space or opening with a solid piece or body, preferably of hardened steel, fitted within said space or opening and replacing certain 30 removable portions of the rails, so as to form at the track intersection the head of the steam-line rail, the inner portion of the head of the guard-rail, and the wheel-bearing and flangeway of the crossing rail. This central piece 35 or body is distinguished from the removable plates heretofore used in certain classes of track structures in that instead of being a shallow piece seated in a pocket in the central body of the structure it itself forms a 40 deep solid central body, to which the adjacent rails are removably secured and constitutes a solid abutment and support for such rails capable of receiving and sustaining the pounding and hammering action of passing 45 car-wheels.

My invention also consists in the novel construction, combination, and arrangement of parts, all as hereinafter described, and pointed out in the appended claims, reference being had to the accompanying drawings, in which—

Figure 1 is a plan view of a track structure embodying my invention, and Fig. 2 a transverse section on the line 2 2 of Fig. 1.

The letter A designates the main rail of the 55 steam-track, B the guard-rail therefor, and C an outer brace-rail, the three rails being placed side by side, as shown, upon a suitable bed or foundation D.

E designates the rails of the intersecting 60 track, these rails being here shown as of the grooved-girder type, with their ends cut obliquely and fitted against the outer sides of the rails B and C, to which they are secured by a suitable bracket F and bolts G. 65

The main rail A has a section thereof at and to each side of the intersection cut away or removed, and the guard-rail B has the inner side of its head also removed for a corresponding distance. In the space thus formed 70 is fitted and seated a solid central body H, preferably of hardened cast-steel, which extends the full depth of the rails, with its sides fitting the webs and heads of the rails B and C in the manner clearly shown in Fig. 2. The 75 upper surface of this piece or body H is formed with a straight wheel-groove or flangeway h, having a gage-line edge h', which forms a continuation of the gage-line of the rail A, and also an intersecting groove or flangeway h², 80 whose gage-line edge h³ forms a continuation of the gage-lines of the girder-rails E, corresponding grooves or flangeways h⁴ being cut across the heads of the rails B and C. It will be seen that the portion of said body or piece 85 to one side of the flangeway h rises to form practically the head of the main rail, while the portion at the other side of the groove rises to form one-half of the head of the guard-rail. It will also be seen that the surface of 90 said piece forms the wheel-bearing of the intersecting track across the line of the rail A. The said piece, therefore, provides the surface for all those parts of the structure which are subject to the greatest wear and also 95 serves to solidly brace and support the adjacent rails, making a very rigid and durable structure. The main through-bolts G extend through holes which are cored in the said body and through the rails B and C, as shown. 100

It is obvious that the exact construction may be varied somewhat to suit various con-

ditions and that the shape of the piece H may be changed to suit differences in the angle of intersection of the two tracks without affecting the spirit and scope of my invention. Hence I do not wish to limit myself to the exact construction, arrangement, and combination of parts which I have herein shown and described.

Having thus described my invention, what I claim as new, and desire to secure by Letters Patent, is—

1. In a track structure of the class described, the combination of the main and crossing track-rails, of a central, solid, hardened body to which the rails are removably secured and which replaces a cut-away portion of the main track-rail, said body having its surface formed with flangeways for both the main and the intersecting tracks and forming a wheel-bearing surface for both tracks across the intersection.

2. In a track structure of the class described, the combination with the main rail having a removable section, the guard-rail having the inner side of its head also removed for a corresponding distance, the brace-rail and the rails of the intersecting track, of a solid hardened body seated between the brace and guard rails and replacing the cut-away and removed portions of the main and guard rails, said body having flangeways for both the main and intersecting tracks.

3. In a track structure of the class described, the combination with the main rail having a section of its length removed, and

the guard-rail having the inner side of its head also removed, of the hardened central body replacing the removed portions of said rails and having flangeways formed therein, together with bolts extending through the said body, and rails binding them together.

4. In a track structure of the class described, the combination with the main rail, the guard-rail, the brace-rail, and the rails of the intersecting track fitted and secured to said guard and brace rails, the latter having flangeways across their heads, of a central body of hardened material seated between the guard and brace rails and forming a section of the main rail and also the inner portion of the head of the guard-rail, together with through-bolts uniting said body to the main guard and brace rails.

5. In a track structure of the class described, the combination with the main rail having a section thereof removed for its full depth, the guard-rail having the inner side of its head also removed for a corresponding distance, and a brace-rail, of the body H of hardened material filling the space formed by the removed portions of the main and guard rails and replacing said portions, said body having flangeways therein for both the main and the intersecting tracks.

In testimony whereof I have affixed my signature in presence of two witnesses.

EDWARD B. ENTWISLE.
